Primary Examiner—Ruth McInroy*Attorney, Agent, or Firm*—Roberts & Mercanti, LLP[57] **CLAIM**

The ornamental design for a handle for a vacuum cleaner, as shown.

DESCRIPTION

FIG. 1 is a front and side perspective view of a handle for a vacuum cleaner showing our new design;

FIG. 2 is a side elevational view thereof, the opposite side being a mirror image;

FIG. 3 is a front elevational view thereof;

FIG. 4 is a rear elevational view thereof;

FIG. 5 is a top plan view thereof; and,

FIG. 6 is a bottom plan view thereof.

The details shown in broken lines on either side of the handle in FIG. 1 are shown for illustrative purposes only and form no part of the claimed design.

1 Claim, 2 Drawing SheetsFIG. 1.

FIG. 2.

FIG. 3.

FIG. 4.

FIG. 5.

FIG. 6.
